Inventor
Paul Miller
By Vernon E. Hodges
his Attorney

UNITED STATES PATENT OFFICE.

PAUL MILLER, OF PHILADELPHIA, PENNSYLVANIA.

EXPANDING REAMER.

Application filed May 15, 1922. Serial No. 561,029.

To all whom it may concern:

Be it known that I, PAUL MILLER, a citizen of the United States, residing at Philadelphia, in the county of Philadelphia and 5 State of Pennsylvania, have invented certain new and useful Improvements in Expanding Reamers, of which the following is a specification.

My invention relates to an improvement 10 in expanding reamers.

The object is to provide an article of the character described, which may be made in different sizes, and which reamer will do the work that heretofore it required six 15 times the number of tools to do, my present invention being made to ream any desired size of hole, say one and one-half to twelve inches (1½" to 12") in diameter, and it has an adjustment of from one-thousandth 20 of an inch upward.

The invention includes comparatively few parts, easy to construct, accurate and effective in operation, and rigid and durable when assembled.

25 In the accompanying drawings:—

Fig. 1 is a sectional view through the body of the tool;

Fig. 2 is an end view;

Fig. 3 is a view of the center guiding- 30 bar;

Fig. 4 is a view of the cones;

Fig. 5 is a view of one of the blades;

Figs. 6 and 7 illustrate split two-piece 35 clamp supports for the blades;

Figs. 8 to 16 inclusive are views of circular nuts;

Figs. 17, 18, 19 and 20 are views of different forms of wrenches;

Fig. 21 is a view of screws for tightening 40 the clamp supports on the body.

A represents the steel body, counterbored from one end, as shown in Fig. 1, partly tapered and partly cylindrical, and provided with radial slots 1, and threaded 45 portions 2 and 3, for purposes that will be explained.

B represents a center guiding-bar, one end 4 of which enters the socket 5 in the inner end of the bore of the body, where it 50 has one flat side 6. The two screws 7 screw down through holes in the side of the body against the flat side 6, holding the center guiding-bar rigidly in place in the axial center of the bore of the body of the tool.

55 The guiding bar has an annular collar 30 formed integral therewith adjacent to the

end 4. This collar is of a diameter to just fit the cylindrical portion of the bore of the body, and its location is such that it abuts against the shoulder 31 at the outer end of 60 the socket when in place, thus making a rigid connection between the guiding bar B and the body when the screws 7 are turned securely against the flat side 6 of the end 4 of the bar. 65

As shown in Figs. 2 and 5, the blades D are fitted within the radial slots 1, in position to be simultaneously adjusted radially, their inner edges tapering, as shown in Fig. 5. 70

Cones C, of which twelve are shown in Fig. 4, are in graduated size, and are adapted to enter the flaring tapering mouth of the bore of the tool body, where they are threaded upon the steel center guiding-bar 75 B, their function being to cause a uniform adjustment outwardly of the steel blades with absolute precision throughout their length. These are inserted from the smallest cone to the next size larger, etc., and 80 forced inwardly upon the center guiding bar until the cones of the required size are in position in engagement with the inner tapering edges of the blades to give them the required outward adjustment. 85

Threads 8, preferably eighteen to the inch, are cut on the guiding-bar B near the end, and a round nut 9 (of which there may be any number of different sizes, two only being shown in Fig. 16) is adapted to 90 be screwed thereon. A wrench 10, (as shown in Fig. 17) with a lever 11, (as shown in Fig. 20) for operating it, is provided for turning the round nut on the thread and up against the cone, whereby the 95 latter are forced along the length of the guiding-bar B, and with uniform pressure outwardly against the blades.

A round nut 12 as shown in Figs. 14 and 15 has external threads which screw into 100 the threads 13 at the outer end of the body, and are provided with a center opening 14, which forms support for the outer end 15 of the center bar B. Thus it will be seen that the round nut 12 acts in conjunction 105 with the special construction at the opposite end of the guiding bar B including the end 4, socket 5, collar 30, the cylindrical bore of the body, shoulder 31 and screws 7, to hold the guiding bar rigidly centered 110 and in place.

A wrench 16, somewhat as shown in Fig.

18, is provided for turning this nut 12. A round nut 17, as shown in Figs. 8, 9 and 10, is screwed on to the threads 2 to form an abutment for the inner ends of the blades D; 5 and a similar nut 21, of which two sizes are shown in Figs. 12 and 13, is adapted to screw on the threads 3 on the outer end of the body portion to afford a support for the outer ends of the steel blades D, thus holding them between the nuts 17 and 21, which afford lateral supports for their ends, and which co-operate with the cones and the nut 9 in the simultaneous and precise outward adjustment of the blades. 10

15 A spanner wrench 23 is provided for adjusting these nuts 17 and 21.

Split two-piece clamp supports E and F, representing different sizes, are inserted outside of the body portion A, and between the 20 blades, and these are split so as to be formed into two taper shaped pieces. Holes 24 are formed part way in each section to receive the screws 25 which hold them in place; and by reason of their tapering slots 26 force 25 the sections apart and rigidly in contact with the opposite sides of the blades.

From the foregoing, it will be seen that a solid, all-metal structure is provided, which may be taken apart, and the various parts 30 of which may be renewed and replaced at any time, and which, by reason of the special form of the various parts and the tools required to separate or assemble them, cannot be tampered with by an unauthorized person, or one who is not provided with the 35 special tools for the purpose.

Thus I have provided a novel, ingenious expanding reamer which is effective in the accomplishment of the functions for which 40 it is intended.

I claim:

1. An expanding reamer including a body counterbored at one end, and the outer portion of the bore tapering, and the corresponding end of the body radially slotted, 45 tool blades fitted in the slots and having tapered inner edges, a center guiding-bar secured axially within the bore of the body, a plurality of graduated cones slidably mounted upon the bar and presenting a smooth conical surface and means for forcing the cones along the length of the bar and against the inner edges of the blades whereby the 50 blades are simultaneously adjusted radially with respect to the body of the tool. 55

2. An expanding reamer including a counterbored body, the outer end of the bore tapering and radially slotted, a center guiding-bar rigidly secured in, and coinciding with, the longitudinal axis of the body, and having threads at or near its free end, blades 60 fitted in the slots, a plurality of graduated cones slidably mounted upon the bar and presenting a smooth conical surface to engage the inner edge of the blades, a nut 65

screwed on the threads of the bar for forcing the cones endwise upon the latter and against the inner edges of the blades for adjusting the latter outwardly simultaneously. 70

3. An expanding reamer including a counterbored body, the outer end of the bore tapering and radially slotted, a center guiding-bar rigidly secured in, and coinciding with, the longitudinal axis of the body, and having threads at or near its free end, blades 75 fitted in the slots, a plurality of graduated cones slidably mounted upon the bar and presenting a smooth conical surface, to engage the inner edges of the blades, a nut 80 screwed on the threads of the bar for forcing the cones endwise upon the latter and against the inner edges of the blades for adjusting the latter outwardly simultaneously, a nut screwed into the outer end of the body, and having a hole to receive and 85 form a bearing for the outer end of the center guiding-bar. 90

4. An expanding reamer including a counterbored body, the outer end of the bore tapering and radially slotted, a center guiding-bar rigidly secured in, and coinciding with, the longitudinal axis of the body, and having threads at or near its free end, blades 95 fitted in the slots, independent graduated cones slidably mounted upon the bar and presenting a smooth conical surface to engage the inner edges of the blades, a nut 100 screwed on the threads of the bar for forcing the cones endwise upon the latter and against the inner edges of the blades for adjusting the latter outwardly simultaneously, and nuts screwed upon the body and against the opposite ends of the blades. 105

5. An expanding reamer including a counterbored body, the outer end of the bore tapering and radially slotted, a center guiding-bar rigidly secured in, and coinciding with, the longitudinal axis of the body, and having threads at or near its free end, blades 110 fitted in the slots, cones slidably mounted upon the bar and presenting a smooth conical surface to engage the inner edges of the blades, a nut 115 screwed on the threads of the bar for forcing the cones endwise upon the latter and against the inner edges of the blades for adjusting the latter outwardly simultaneously, split two-piece clamp supports, the sections of which taper and have holes formed partly in each section and adapted to be inserted between the blades, and screws having tapering heads which extend into said holes and into the body, which when screwed in place force the sections of the clamps in opposite directions against the 120 blades. 125

6. An expanding reamer including a body portion counterbored, the outer ends of the bore conical, and that portion of the tool 130 radially slotted, blades fitted to the slots and having tapering inner edges, a center

guiding-bar secured within the bore of the body, graduated cones adjustable thereon and presenting a smooth conical surface and bearing against the inner edges of the blades, 5 means adjustable upon the guiding-bar for forcing the cones lengthwise, means screwed into the outer end of the body to form a support for the outer end of the guiding-bar, and means screwed upon the body to form 10 lateral support for each end of the blades.

7. In an expanding reamer, the combination with a radially slotted counterbored body having a socket at the inner end of the bore, of a center guiding-bar having 15 one end fitted to the socket, said end flat on one side, screws extending into the body against the flat side for holding the guiding-bar securely in the socket, and a round nut screwed into the outer end of the body, and 20 having a hole which receives and forms a bearing for the outer end of the guiding bar, cones slidably mounted on the guiding bar, and blades fitted to the slots in position to be uniformly adjusted by the cones.

25 8. In an expanding reamer, the combination with a counterbored body radially slotted, blades fitted to said slots, means for adjusting the several blades outwardly simultaneously, split clamps made of tapering 30 sections having holes formed part in the adjacent edges of each section, and screws having tapering heads which extend through said holes into the body, which when driven home force the sections outwardly, and 35 crowd them against the sides of the blades forming rigid lateral supports therefor.

9. In an expanding reamer, the combination with a counterbored body radially slotted, blades fitted to said slots, adjustable 40 means for supporting the ends of the blades, means for adjusting the several blades outwardly simultaneously, split clamps made of tapering sections having holes formed part in the adjacent edges of each section, and screws having tapering heads which extend through said holes into the body, which when driven home, force the sections outwardly and crowd them against the sides of 45 blades forming rigid, lateral supports therefor.

50 10. An expanding reamer including a counter-bored radially slotted body, blades adjustable in the slots, three separate adjustable clamping means engaging the opposite ends of the blades, two of which means are located at one end of the blades, one within the bore of the body and the other externally of the body whereby to engage the blades at two different radial 55 distances from the longitudinal axis of the body.

60 11. An expanding reamer counterbored and radially slotted and having a socket at the inner end of the bore of less diameter than the adjacent bore, a guiding bar hav-

ing an end fitted to the socket and provided with a collar which fits the bore adjacent to the socket, means for securing the end rigidly in place in the socket, a set of graduated cones, a plurality of which in regular 70 sequence may be slidably mounted, upon the guiding bar and blades fitted to the radial slots against the inner edges of which the cones engage.

12. An expanding reamer counterbored 75 and radially slotted and having a socket at the inner end of the bore of less diameter than the adjacent bore, a guiding bar having an end fitted to the socket and provided with a collar which fits the bore adjacent 80 to the socket, means for securing the end rigidly in place in the socket, graduated cones adjustable on the guiding bar, blades fitted to the radial slots against the inner edges of which the cones engage, a round 85 nut screwed into the outer end of the bore against the outer ends of the blades and having a hole to receive the outer end of the guiding bar and a nut screwed on the outer end of the body and engaging and 90 holding the outer ends of the blades.

13. An expanding reamer including a counterbored body having radial slots, blades fitted to and movable in said slots with their several inner edges presenting a 95 single continuous conical formation, a plurality of graduated wedging elements adapted to engage and be forced simultaneously and uniformly against the inner edges of the blades whereby to adjust the several 100 blades simultaneously and uniformly.

14. An expanding reamer including a counterbored body having radial slots, blades fitted to and movable in said slots with their several inner edges presenting a 105 single continuous conical formation, a plurality of round graduated wedging elements adapted to engage and be forced simultaneously and uniformly against the inner edges of the blades whereby to adjust the 110 several blades simultaneously and uniformly and means for forcing said elements end-wise in the conical spaces formed by the inner edges of the blades.

15. An expanding reamer including a 115 counterbored body having radial slots, blades fitted to and adjustable in said slots, said blades each having a single continuous tapering inner edge, a centering bar located in the axial center of the reamer, a plurality 120 of wedging devices adapted to be slidably mounted on the bar in position to engage the inner edges of the several blades, means for forcing said devices end-wise on the bar to adjust the blades and means for locking the blades in place in their respective slots, after having been adjusted.

16. An expanding reamer including a body having a bore formed throughout its center, a portion of which is cylindrical, a 125

- center guiding-rod having a cylindrical portion which fits and is held in the cylindrical portion of the bore, and provided with screw threads, radially adjustable blades, cones slidably mounted on the rod for engaging the inner edges of the blades, and simultaneously adjusting them uniformly throughout their length, and a nut screwed on the threads of the rod for adjusting the cones.
17. An expanding reamer including a body having a bore formed throughout its center, a portion of which is cylindrical, a center guiding rod having a cylindrical portion which fits and is held in the cylindrical portion of the bore, and provided with screw-threads, radially adjustable blades, cones slidably mounted on the rod for engaging the inner edges of the blades, and simultaneously adjusting them uniformly throughout their length, a nut screwed on the threads of the rod for adjusting the cones, and nuts secured on the body portion at opposite ends of the blades for locking the latter in adjusted position.
18. An expanding reamer including a body having a bore formed throughout its center, a portion of which is cylindrical, a center guiding rod having a cylindrical portion which fits and is held in the cylindrical portion of the bore, and provided with screw-threads, radially adjustable
- blades, cones slidably mounted on the rod for engaging the inner edges of the blades, and simultaneously adjusting them uniformly throughout their length, a nut screwed on the threads of the rod for adjusting the cones, nuts secured on the body portion at opposite ends of the blades for locking the latter in adjusted position, and a nut screwed into the outer end of the body and having a central hole to hold and support the outer end of the rod.
19. An expanding reamer including a counterbored radially slotted body portion, a portion of the bore being cylindrical, and one end of the bore gradually tapering from the cylindrical portion to the end, a center guiding rod insertable in the bore by way of said tapering portion of the bore, said rod having a threaded outer end and a cylindrical portion adapted to fit the cylindrical portion of the bore and be secured therein, a nut screwed on the threads, blades fitted to and adjustable in the slots, elements slidably mounted on the rod engaging the inner edges of the blades and adjustable on the rod by the turning of the nut, and means for centering and supporting the outer end of the rod in the tapering end of the body.

In testimony whereof I affix my signature.

PAUL MILLER.
